KEYBOARD OPERATED CODE
TRANSMITTERRichard E. Mathes, Westfield, N. J., assignor to
Radio Corporation of America, a corporation
of Delaware

Application February 5, 1942, Serial No. 429,648

12 Claims. (Cl. 178—80)

This invention relates to keyboard transmitters for telegraph systems and more particularly to a transmitter of the type which is adapted to transmit synchronized signals.

In ordinary start-stop keyboard transmitters no continuous synchronization is required between the transmitting and receiving stations since the cyclic transmission of each code signal as initiated at the transmitter is closely enough followed by the speed of operation of the receiving instrumentality. The keyboard transmitter which constitutes the subject matter of the instant invention, however, is one which transmits the code signals for each character in a predetermined time relation to the operation of a time division simplex or multiplex distributor. Such a distributor may be run continuously and a receiving distributor can be maintained in synchronism with the transmitting distributor by well known means.

In the synchronized signal transmission systems for which my invention is best adapted to be used there is no provision for operating printers on the start-stop principle. For this reason transmission is normally effected by perforating a transmission tape with the desired signals. Tape perforators for this purpose have been known in the art for a considerable time. One embodiment of such a perforator is described in a book entitled "Printing Telegraph Systems and Mechanisms" by H. H. Harrison, published by Longmans, Green & Company. On page 167 of this book is a brief description of a similar known keyboard perforator, reference being made to Fig. 165 on page 166. That is a perforator of the so-called "Morkrum" system.

One of the disadvantages of using perforated tape for signal transmission is that a certain delay in the transmission itself must of necessity occur after the tape has been perforated. This fact is due to the impracticability of immediately utilizing the tape perforations for transmission after a given portion of the tape has been punched by the keyboard. For certain types of communication and classes of traffic such delays cannot be tolerated.

It is, therefore, highly desirable that the electrical signals be available for transmission within a fraction of a second after operation of the sending keyboard. My invention, therefore, contemplates utilizing a conventional keyboard perforator having modifications incorporated therein such as to permit immediate transmission of signals by direct control of certain code contact

springs in association with a synchronous distributor.

It is, therefore, an object of my invention to provide modifications of a keyboard perforator such as will provide for direct transmission, not from the perforated tape, but from contact springs directly controlled by the keyboard.

It is another object of my invention to provide a combination of direct keyboard transmitter and tape perforator such that, when messages have been transmitted by direct keyboard operation, a perforated tape shall simultaneously have been prepared for record purposes at the transmitting station and for repeating the messages, if necessary.

Other objects and advantages of my invention will be made apparent in the more complete description to follow. This description is accompanied by drawings to which reference will be made for a clearer understanding of the invention. In the drawings:

Fig. 1 shows in perspective certain component parts of a keyboard perforator and transmitter sufficient for a clear description of my invention; and

Fig. 2 shows a circuit diagram of the connections which in a preferred embodiment of my invention are necessary to establish operating association between a keyboard transmitter and a synchronous transmitting distributor.

Referring to Fig. 1, I show therein a key bar 10 which is only one, of course, of the entire group of key bars of the keyboard. This key bar is pivoted at 11 and carries a code selector comb 12 which may be affixed thereto in any suitable manner, as, for example, by rivets 13. The selector comb may, however, be welded on if desired; or in certain instances it may be formed integrally with the key bar. Beneath the comb

12 is an arrangement of loop bails P, and 1 to 7 inclusive. The bail P is actuated by each and every key and has the function of actuating a certain lever system which stores and locks a given set-up of contacts, together with associated punch levers, until transmission of the selected code signal has been effected. In the embodiment shown the function of the bail P is modified with respect to its normal function in the conventional keyboard perforator. That normal function heretofore has been to close a contact of a switch for electromagnetically driving the punch hammer and the tape feed device of the perforator. As will be hereinafter explained, the electromagnet for actuating the punch and tape feed device according to my in-

vention is controlled by a local circuit closed periodically at a particular phase of rotation of the transmitting distributor.

The loop bails 1 to 7 inclusive serve when they are actuated for immobilizing their respective punches and simultaneously for opening corresponding contacts of the signal code composing circuits. These loop bails are all pivoted on the pivot rod 9. Above this pivot rod the bails extend upwardly, these extensions being indicated at 14. Certain shoulders on the extensions 14 are of variable height, but each is notched for engagement with a bell crank 15. There are seven of these bell cranks, each corresponding with one of the elements of a 7-unit code signal. They are all mounted on a vertical pivot rod 16. On this same pivot rod is also mounted a lever arm 26 which engages with a notch in the vertical extension 27 operable from and by the bail P.

Since the perspective view of Fig. 1 is taken from a point in the rear and to the right of the keyboard perforator, the extensions of the bell cranks 15 which appear to the left of the pivot center 16 will be understood to be forward extensions of these bell cranks. Unlike the conventional bell crank extensions, they terminate pointedly beyond the linkage centers 11. These pointed ends are arranged to be engaged by a wedge-shaped member 28 which is movable forwardly and backwardly in order to provide a lock for storing the set-up of each signal until after it has been transmitted.

The forward ends of the bell cranks are pivotally connected at 17 to control arms 18 which extend within the assembly consisting of a die and stripper plate, punch block, guide plate, shedder, and shedder wearing strip shown generally at 19. The details of construction of this assembly are not herein described since they are well known in the art.

According to my invention the conventional loop bail extensions 14 are still further extended in vertical portions 29 all of which reach an equal height. At the top of each extension 29 and bearing against the back edge thereof are insulation blocks 30 supported by contact springs 31. Each contact spring 31 has a contact button which is normally pressed into contact with a bus bar 32. This bus bar 32 is connected with a contact 33 (as shown in Fig. 2) and, when any combination of the bell cranks 15 is actuated, connection is made between the contact 33 and a contact spring 34. The latter is supplied with signalling energy from any suitable source, here indicated as the positive terminal of such a source, the negative terminal being understood to be grounded. Actuation of the spring 34 is obtained by pressure of a plurality of bell cranks 15 against the vertical actuating bar 35. When this bar is not actuated, current is supplied through the contact 34 to three back contacts 36 which are used for transmission of a "blank" signal. This signal is not used for typewriter spacing, but fills in the signalling time of the transmitting distributor whenever the keyboard operator fails to actuate his keys in step with the distributor. This condition will be discussed hereinafter.

The wedge-shaped member 28 terminates above and below in a backward extension to which springs 37 are attached. These springs are drawn rearwardly by attachment to the pivot rod 16. The member 28 is also suitably held in place by guides (not shown), but it is free to slide for-

ward and backward. The springs 37 tend to pull it backwardly.

I have also provided sets of levers 38 and 39 for the purpose of forcing the member 28 into its forward position. Lever 38 is pivoted at 40, whereas lever 39 is pivoted at 41. The punch hammer 21 is of conventional construction. The lever 38 is arranged with a forwardly projecting hook 38a so that when the punch hammer 21 is moved forwardly lever 38 will rotate though a small angle about the pivot center 40, thereby moving lever 39 in a direction to drive the wedge-member 28 forwardly and out of engagement with the pointed ends of the bell cranks 15. Although the return (back) stroke of the punch hammer 21 follows its forward stroke immediately upon deenergization of the operating magnet 25, I have arranged to lock the wedge-member 28 forwardly in dependence upon deenergization of the punch hammer magnet 25 and to unlock the wedge-member 28 in dependence upon a subsequent actuation of a key 10. The mechanism for accomplishing this includes lever arms 26 and 42, the latter being horizontally pivoted at 43. One end of the lever 42 is tapered and fits under the lever 26. The other end of lever 42 has a shoulder on the under side to fit over the end of the backward extension 28a which is integral with the wedge-member 28. It will be clear from the perspective view of Fig. 1 that prior to a key depression the back edge of the extension 28a will rest in the recess under the end of lever 42. This forward end of lever 42 is raised upon key depression, at which time bail P operates to move lever 26 against the tapered slope at the back end of lever 42. Then the springs 37 are allowed to contract, thus drawing the wedge member 28 backwardly into engagement with the pointed ends of the bell cranks 15. This locks these bell cranks in whichever position they have been set by key depression. Unlocking takes place only after the wedge-member 28 has been removed (forwardly) from engagement with the bell crank levers, that is, upon actuation of the punch magnet 25. At this moment the forward end of lever 42 is allowed to drop by gravity (aided by a spring if desired) so that the underlying shoulder near the end of this lever will engage with the back edge of the extension 28a. This engagement locks the wedge-member 28 in its forward position of disengagement with the bell cranks until such time as a subsequent key is depressed.

In the operation of my invention a message to be transmitted is both perforated on the tape 58 and is caused to set up code combinations for each depression of one of the keys 10 of the keyboard. According to the 7-unit code system, which is preferably used in connection with my keyboard transmitter, each key depression causes three and only three holes to be punched in the tape by withdrawing selected ones, four in number, of the levers 18 from the path of the punch lever 21 opposing respective punches within the punch block assembly 19.

Each key when depressed selects for actuation suitable ones of the bails 1 to 7 inclusive, four in number, not only to actuate the bell cranks 15, but also to open four selected contacts on the springs 31, leaving only three of these in engagement with the bus bar 32. The actuation of the extension pieces 29 on the upstanding extensions 14 for code composing purposes has already been explained.

In Fig. 2 it will be observed that each of the

contact springs 31 is connected directly or indirectly with certain segments 51 of a rotary distributor. The distributor itself is shown in developed form. Associated with the segments 51 is a bus ring 52 which is connected to transmitting equipment of any suitable type, such as a keying circuit for a radio transmitter. Assuming that the brush 53 rotates at a predetermined transmission speed as controlled by synchronizing impulses, the code combinations will obviously be collected by passage of this brush 53 successively over the respective segments 51. Thus, each code combination will be immediately transmitted upon depression of its appropriate key. The operation of the keyboard to perforate the tape is also performed in a conventional manner.

In order to permit the transmission of a succession of code impulses substantially without interruption it is necessary to store at least a portion of each code signal in a storage device such as shown at 54. The details of this storage device are not herein given since reference may be made to a similar storage device described in an application of James A. Spencer, Serial No. 357,109, filed September 17, 1940, now Patent No. 2,327,075, granted Aug. 17, 1943. Reference is here made to Fig. 1 of that application for showing how a part of the code signal may be electromagnetically stored and subsequently transmitted in proper sequence with respect to the code elements for which direct connections are made between the transmitting contacts and the distributor.

In conformity with Spencer's system aforementioned, I show individual circuits between contacts 31 and the first four segments of the distributor ring 51 (Fig. 2), while the remaining contacts 31 are connected to the windings of appropriate storage relays (not shown) in the device 54. These relays are locked up automatically upon completing their operating circuits through the contacts of a timing relay under control of an impulse from source 57 through bus ring 55 and segments d_2 and d_3 which feed conductor 59 when swept over by brush 56. The same storage relays possess contacts through which impulses are transferred to the 5th, 6th, and 7th segments of distributor ring 51, for completing the transmission of each code combination. At the commencement of the next revolution of the brush 56, a "clearing" relay (not shown) is actuated for unlocking the three storage relays. This actuation takes place upon passage of brush 56 over segment d_1 . It will thus be seen that these relays constitute means for introducing a "hang-over" of effects produced by the closing of the contacts 31 so that the code bars operated by the keys 10 may be returned to normal and the contacts 31 opened even before the brush 53 has traversed the segments 51 connected to the storage device 54.

The actuation of the punch magnet 25 is accomplished by means of a local circuit closed by brush 56 passing over segments d_5 and d_6 , this function being thus timed to follow the scanning of the code elements as set up on the contacts 31. The code signals are thus perforated in the tape while they are being transmitted to the keying circuit. Furthermore, the operation of the punch hammer 21 causes the wedge-member 28 to be driven into a position of disengagement from the pointed ends of the bell cranks 15. The bell cranks are then free to be restored to normal positions. A subsequent key depression causes another combination of bell cranks 15 to be moved across the apex of the wedge-member 28, and

since the latter is also released by lever 42, the bell cranks are locked in their actuated positions until the next energization of the punch magnet 25.

Should the operator depress two keys within a single cycle of the distributor, it is true that an improper signal might be transmitted. Such a signal, however, would contain more than three marking elements, and, in accordance with the prevailing practice in the use of a 7-unit code signal system, such erroneous signal would be indicated by an error indication. All correct signals will be understood, therefore, to consist of three marking elements.

For continuous sending the keyboard must be operated in cadence with the local pulses through the brush 56 and segment 55 of the distributor. However, as this is difficult for operators and requires highly specialized training, I have provided for a "blank" signal to be transmitted whenever the operator skips a beat of the operating magnet 25. This is the purpose of the three contacts 36 which engage with the contact spring 34. When the contact spring 34 engages with contacts 36 no current is supplied to the bus bar 32; hence in the absence of key depression a code signal consisting of three elements in the fifth, sixth, and seventh positions, for example, will be transmitted through contacts 36 and associated segments 51 of the distributor. The receiving printer performs no operating function when this "blank" signal is received, but the fact that the signal is composed of three marking units permits the error detector to count it as correctly received and therefore no error designating symbol will be printed as would be the case upon reception of a mutilated signal.

It will, of course, be understood by those skilled in the art that modifications of my invention may be made without departing from the spirit thereof.

I claim:

1. A keyboard-operated code signaling device having in combination, a set of keys arranged in a keyboard, a tape perforator having code punches selectively operable under control of the keyboard keys, means including a continuously driven transmitting distributor for timing the operation of punching code elements in a tape and for successively transmitting the several code elements of each character signal selected by said keys, a plurality of contact devices arranged for selective actuation by said keys in accordance with code signals to be transmitted, and in agreement with the code elements to be punched in said tape, and means for causing the code elements of each signal to be punched in said tape during the time occupied in transmitting the same signal from said contact devices through said distributor to a telegraph channel.

2. The method of utilizing the keyboard of a tape perforator for direct keying of telegraph signals, where the apparatus involved includes code-element contactors corresponding to the several code punches in said perforator, and a continuously running distributor, which method includes simultaneously setting up the same code element combination in said punches and in said contactors, and transmitting through said distributor at least a portion of a given code combination before punching the same in the tape.

3. In code-signal transmitting equipment, a keyboard-operated tape perforator having code element selective means, including bails underlying a set of key bars, for determining different

permutations of holes to be punched in a tape, locking means operable upon each key depression for momentarily storing successive settings of said selective means, continuously operable distributor means for effecting successive transmission of the code elements of each signal, means electrically in circuit with said distributor means and operable under control of said keybars and bails for composing the code elements of each signal, and means periodically operable by said distributor means for causing each signal permutation so composed to be transmitted through said distributor and for simultaneously perforating the code elements of the same signal in said tape.

4. In a keyboard transmitter, a group of code element contactors normally held in marking positions and selectively settable to spacing positions in accordance with the spacing units of a code signal, an assembly of keys, keybars, code element bails selectively operable by the keybars, and lever mechanism for selectively setting said contactors, a continuously operable distributor having segments corresponding to said contactors, means for effecting the transmission of a code signal through said contactors and said distributor segments in response to the actuation of an appropriate key, and tape perforator means settable by said keys and operable in cyclic accord with said signal transmitting means for storing in tape a code combination of perforations corresponding with the marking elements of the transmitted signal.

5. In a transmitter of the type defined by claim 4, means operable by the keys of the keyboard for locking selected ones of said contactors in open-circuit positions until the next succeeding course of said distributor through one cycle.

6. In a transmitter of the type defined by claim 4, means automatically effective whenever the keyboard operator fails to depress a key in advance with the cyclic operation of said distributor, for transmitting a "blank" signal through said distributor.

7. In a telegraph system which requires the use of a keyboard-operated tape perforator and a transmitting distributor having segments corresponding to the code elements of the signals and other segments serving to rhythmically control the operations of the system, the method which comprises running said distributor continuously, manipulating the keys of the keyboard to set up each combination of code elements according to selected characters, causing certain impulses representing a portion of each said code combination to be sent out from appropriate segments of said distributor, momentarily storing another portion of said code combination and causing the impulses thereof to be likewise sent out from appropriate segments of said distributor, causing an impulse through at least one of said operation-controlling segments to actuate the perforator thereby to punch holes in the tape corresponding to the code signal then being transmitted, and causing another impulse through at least one of said operation-controlling segments to terminate the storage of said code elements.

8. In a keyboard-controlled system for transmitting uniform length character signals through

permutationally selected contacts and through corresponding segments of a continuously operable distributor, and for simultaneously perforating a tape in accordance with said character signals, the method which comprises manipulating the keys of said keyboard, causing such manipulation to momentarily store the code elements of each successive character signal, causing the transmission of said signals to be timed by the cyclic operation of said distributor, causing the storage of said code elements to cease at a particular cyclic phase of operation of said distributor, and effecting the perforation of each code signal in said tape in cyclic accord with the electrical transmission of the same code signal.

9. A keyboard-operated code signaling device having means for permutationally punching holes in a tape and for feeding said tape across a punching position, mechanism for momentarily storing a condition representing a permutational set-up of code elements to be punched in said tape corresponding to a character selected by key actuation, a transmitting distributor having continuously driven brushes and segments corresponding to the code elements, contact devices for feeding a signal potential to selected ones of said segments and thence through a first one of said brushes to a communication channel, locking means for maintaining each code set-up during a period commencing with the actuation of a selected key and including the passage of said brush over predetermined ones of said distributor segments, storage means connected to the remaining segments and actuatable prior to the sweeping of said brush thereover for producing a "hang-over" of said code set-up beyond the maintenance period of said locking means, and means including local circuits closeable by a second one of said brushes for performing a punching operation on said tape and for subsequently terminating the effective period of said locking means.

10. In combination, a keyboard-operated code composing mechanism, a tape perforator having punches selectable by said mechanism, a set of code-element contacts selectively closeable by said mechanism, a continuously operable distributor through which circuits individual to the code elements of a character signal are successively connected to a line, and periodic timing means operable in synchronism with said distributor for causing selected punches of said perforator to perforate a tape, thereby to record the selected code element combinations simultaneously with the signal transmission thereof.

11. The "combination according to claim 10 and including a plurality of "blank"-signal-composing contacts and means for causing the same to be effective for transmitting a blank signal whenever the operation of said code composing mechanism ceases to be maintained in step with said distributor.

12. The combination according to claim 10 and including relays in certain of said code element circuits, said relays constituting means for introducing a "hang-over" of effects of said code composing mechanism after the latter has been restored to normal.

RICHARD E. MATHES.
